UNITED STATES PATENT OFFICE.

EDWARD W. SEYMOUR, OF NEW YORK, N. Y.

POCKET FLASH-LIGHT.

1,248,934.

Specification of Letters Patent. Patented Dec. 4, 1917.

Application filed September 23, 1916. Serial No. 121,712.

To all whom it may concern:

Be it known that I, EDWARD W. SEYMOUR, a citizen of the United States, residing at New York, in the county of New York and State of New York, have invented certain new and useful Improvements in Pocket Flash-Lights, of which the following is a specification.

This invention relates to pocket lights and more particularly to electric pocket flash lights having the electric light, battery and controlling means simply and compactly arranged within a suitable casing.

One of the objects of the present invention is to provide a simple and practical electric pocket flash light of the above general character having few parts whereby the same may be easily and quickly assembled and manufactured at a minimum expense.

A further object is to provide a device of the first above-mentioned character in which the parts are so positioned and arranged as to prevent movement and rattling thereof when the same is handled and consequent wear of the parts.

Other objects will be in part obvious from the annexed drawings and in part indicated in connection therewith by the following analysis of this invention.

This invention accordingly consists in the features of construction, combination of parts, in the unique relations of the members, and in the relative proportioning and disposition thereof, all as more completely outlined herein.

To enable others skilled in the art so fully to comprehend the underlying features thereof that they may embody the same by the numerous modifications in structure and relation contemplated by this invention, drawings depicting a preferred form have been annexed as a part of this disclosure, and in such drawings, like characters of reference denote corresponding parts throughout all the views, in which—

Figure 1 is a longitudinal sectional view of the complete device in normal position;

Fig. 2 is a similar view of a portion of the device showing a modification;

Fig. 3 is a similar view showing a modified form of non-rattling washer;

Fig. 4 is a detail elevation of the rear end of the battery cell of a modified construction. In this view, the usual insulating

wrapping or sheath of the shell is shown in section in the interest of clearness.

Referring now to the drawings in detail and more particularly to Fig. 1, 5 designates an outer cylindrical shell made of a single piece of tubing having stamped out threads at 6 at one end into which a lamp socket 7 is adapted to be screwed. A small electric bulb 8 provided with a base 9 is adapted to be screwed into the socket plug and is provided at its rear end with a contact 10 adapted to be engaged by one of the terminals 11 of a cylindrical battery cell 12 contained in the body 5. The opposite end of this battery is provided with a contact plate 13 adapted to be engaged by a push button 14 mounted in a threaded plug 15 screwed into the threaded end 17 of the casing 5. The contact end 16 of the push button 14 has riveted thereto a washer 20 to prevent removal thereof by the reaction of a coil spring 18 normally holding the push button in the position shown in Fig. 1.

This washer 20 surrounds the pin near its contact end and lies adjacent the plug 15. An insulating washer 21 is carried by plug 15 and is adapted to hold the battery firmly in place and prevent movement or rattling thereof. It will be noticed in the form shown in Fig. 1 that this washer is die stamped out of suitable insulating material to closely fit an annular groove formed by two shoulders 22 and 23 in plug 15 and is held positively thereby as said plug is screwed into or out of the casing. The washer may be of elastic or non-elastic material.

In Fig. 2, substantially the same arrangement of parts is to be found except that an insulating and non-rattling washer 24 is made slightly larger and plug 15 is provided with only one shoulder 25 upon which the washer is forced and is held in place by its frictional contact.

In Fig. 3, a still further modification of the washer is shown. In this modification the washer 26 is provided with a recess formed by an enlarged shoulder 27 into which the end of the battery 12 fits snugly. This washer is so shaped as to grip the outer surfaces of the end of the battery and to be carried thereby, and when the plug 15 is screwed into place it not only prevents endwise movement but also lateral movement of

the battery with respect to the casing 5. In this manner wear of the inside of the metal tube or other construction material is eliminated, and the insulating or non-conductive material, preferably fiber, of the washer 26 will permit the operation of the push button or plunger 14 therethrough. The manner in which the parts are constructed and fitted one within the other permits the plug casing 10 and battery to be taken apart without danger of loss of the washer, as would occur if the washer were loosely mounted instead of closely fitting one of the parts with which it is associated.

15 Fig. 4 shows an insulating washer 27 of the same outside size and diameter as the outside casings of the battery cell 12 and forms one of the parts of the battery construction. It is inclosed and held permanently in place 20 by the common insulating material used to cover and finish the battery casings.

It is believed that the method of use and operation of a device of this character is clear and will be understood by those familiar with the subject. The device may be 25 said to comprise but three parts, that is, the casing with its lamp, the battery and the push button.

This method of construction and use of 30 the parts as shown does away with any air opening or aperture through the shell case, thus protecting the battery from any atmospheric action, affording clearly a damp and moisture proof outside case, and provides a confined air envelop around battery 35 and interior, when all parts are screwed together.

This invention is simple and practical in construction, inexpensive to manufacture, 40 and accomplishes, among others, all of the objects and advantages above set forth.

I realize that considerable variation is possible in the details of construction and arrangement of parts without departing from 45 the spirit of my invention, and I therefore do not intend to limit myself to the specific form shown and described.

What I claim is:

1. In a device of the class described, a 50 casing provided at its forward end with a lamp socket adapted to receive an electric lamp, a plug screwed into the rear end of said casing, a battery cell clamped between the plug and the contact of the lamp, a washer of insulating material positioned intermediate the plug and battery cell and secured to one of them, to preclude rattling of the battery cell within the casing when the parts are in assembled relation, and push-button switch mechanism mounted within the 55 plug.

2. In a device of the class described, the combination of a casing provided at its forward end with a lamp, a battery cell within 60 the casing, a push-button member screwed

into the rear end of the casing, and a washer of insulating material secured to said push-button member and rigidly engaging the battery cell, for the purpose of precluding rattling of said cell within the casing.

3. In a device of the class described, the combination of a casing provided at its forward end with an electric lamp, a push-button member screwed into the rear end of said casing, a battery cell clamped between the lamp and the push-button member, a spring-retracted push-button carried by said member, and a washer of insulating material, permanently secured by an annular ring on said member, interposed between said member and the battery cell for precluding rattling of the battery cell within the casing.

4. In a device of the class described, the combination of a casing provided at its forward end with an electric lamp, a push-button member screwed into the rear end of the casing, a battery cell clamped between the lamp and the push-button member, a spring-retracted push-button carried by said member, and an insulating washer frictionally carried on an annular shoulder on said member, the inner end of the push-button being provided with an enlargement adapted to prevent its removal through said member.

5. In a device of the class described, the combination of a casing provided at its forward end with a lamp socket, a lamp, provided with a contact, adapted to seat in said socket, a plug for closing the rear end of the casing, and a battery cell, provided at its opposite ends with contacts, positioned within the casing and clamped between the plug and the lamp, with the contact of the lamp in engagement with the contact of the cell, and push-button switch mechanism mounted on said plug and insulated with respect to the battery cell, said push-button switch mechanism being coöperable with the contact at the rear of the cell for completing a circuit through the lamp.

6. In a device of the class described, the combination of a casing, an electric lamp mounted at the forward end of said casing, a battery cell positioned within the casing 115 and provided at its opposite ends with contacts, means for closing the rear end of the casing and simultaneously clamping the battery cell against the lamp, with the contacts of the lamp and cell in engagement with one another, switch mechanism, normally free from engagement with the rear contact of the cell, carried by the casing closing means and adapted, when operated, to engage with the contact at the rear end of the battery cell for completing a circuit through the lamp, and means for normally maintaining said switch mechanism in circuit-breaking position.

7. In a device of the class described, a 130

- casing, a lamp, provided with a contact, mounted at the forward end of said casing, and a battery cell, provided with contacts at its opposite ends, positioned within said casing, in combination with a member for closing the rear end of said casing and simultaneously forcing the forward contact of the battery cell into engagement with the contact of the lamp, and push-button 10 switch mechanism, normally free from electrical connection with the cell, carried by said member and adapted, when operated, to engage with the cell to complete a circuit through the lamp.
- 15 8. In a device of the class described, a casing, a lamp, provided with a contact, mounted at the forward end of said casing, and a battery cell, provided with contacts at its opposite ends, positioned within said 20 casing, in combination with a member for closing the rear end of said casing and simultaneously forcing the forward contact of the battery cell into engagement with the contact of the lamp, and a normally retract- 25 ed push-button switch carried by said mem- ber and insulated from the battery cell, which push-button switch is adapted, when actuated, to engage with the rear contact of the cell for the purpose of completing a cir- 30 cuit through the lamp.
9. In a device of the class described, a casing, an electric lamp, provided with a contact, at the forward end thereof, a bat- 35 tery cell, provided at its opposite ends with contacts, positioned within the casing, a member for closing the rear end of said casing and simultaneously forcing the for- ward contact of the battery cell into en- gagement with the contact of the lamp, and a spring-retracted push-button operable 40 through said member to engage with the rear contact of the cell, said push-button being, in its re- 45 tracted position, insulated from the cell, but in electrical communication with the lamp, whereby, when the but- ton is actuated to engage with the rear con- tact of the cell, a circuit is completed through the lamp.
10. In a device of the class described, a casing, an electric lamp, provided with a 50 contact, at the forward end thereof, a bat- tery cell, provided at its opposite ends with contacts, positioned within the casing, a member for closing the rear end of said cas- 55 ing and simultaneously forcing the forward contact of the battery cell into engagement with the contact of the lamp, a spring-re- tracted push-button operable through said member to engage with the rear contact of the cell, said push-button being, in its re- 60 tracted position, insulated from the cell, but in electrical communication with the lamp, whereby, when the button is actuated to engage with the rear contact of the cell, a circuit is completed through the lamp, and 65 cushioning means, positioned intermediate said member and the cell, for centralizing the cell within the casing and precluding rattling of the cell within said casing.
- In testimony whereof I affix my signature 70 in presence of two witnesses.
- EDWARD W. SEYMOUR.
